[57] CLAIM

The ornamental design for a weatherproof cover assembly, substantially as shown and described.

DESCRIPTION

FIG. 1 is a perspective view of a weatherproof cover assembly embodying my new design;

FIG. 2 is a bottom view thereof;

FIG. 3 is a top view thereof;

FIG. 4 is a side view taken from the left of FIG. 1;

FIG. 5 is a front view thereof;

FIG. 6 is a rear view thereof;

FIG. 7 is a perspective view of a second embodiment of the design of FIG. 1;

FIG. 8 is a bottom view of FIG. 7;

FIG. 9 is a top view of FIG. 7;

FIG. 10 is a side view taken from the left of FIG. 7;

FIG. 11 is a front view of FIG. 7;

FIG. 12 is a rear view of FIG. 7;

FIG. 13 is a perspective view of a third embodiment of the design of FIG. 1;

FIG. 14 is a side view taken from the left of FIG. 13;

FIG. 15 is a bottom view of FIG. 13;

FIG. 16 is a top view of FIG. 13;

FIG. 17 is a front view of FIG. 13;

FIG. 18 is a rear view of FIG. 13.
